UNITED STATES PATENT OFFICE.

JAMES THOMPSON, OF BOSTON, MASSACHUSETTS, ASSIGNOR OF ONE-HALF
TO LIVERUS HULL, OF SAME PLACE.

BELT-FASTENER.

SPECIFICATION forming part of Letters Patent No. 309,808, dated December 23, 1884.

Application filed May 5, 1884. (No model.)

To all whom it may concern:

Be it known that I, JAMES THOMPSON, of Boston, county of Suffolk, State of Massachusetts, have invented an Improvement in 5 Belt-Fasteners, of which the following description, in connection with the accompanying drawings, is a specification, like letters on the drawings representing like parts.

My improved belt-hook is composed of a single piece of wire bent to form a series of holding-bars with projecting hooked fingers, the holding-bars and points of the fingers being upon the same side of the belt. For the production of my improved hook wire in long 10 lengths or on rolls may be bent by machinery, and be provided with fingers of the proper length, and thereafter the bent strip may be cut into short lengths to correspond with the width of the belt to be joined. The construction of my improved hook is such that, if desired, the abutting ends of the belt may be double-fastened, each end of the belt having applied to it one of the hooks, the fingers of each hook engaging the opposite end of the belt and fitting between the fingers of the other hook.

Figure 1 represents one of my belt-hooks; Fig. 2, an end view thereof; and Fig. 3 represents one of my improved hooks applied to a belt, the dotted lines showing a second hook applied as it may be for double-fastening the ends of the belt.

In the production of belt-hooks embodying my invention a piece of wire, taken preferably from a roll or coil, is bent at intervals to form lateral branches, all at one side, to constitute fingers *a*, which at their ends are all turned

upward in one direction to form hooks *b*. The branches *a* are sufficiently distant one from the other to leave holding-bars *c*, and the parts *c* of the wire are of a length suitable for the thickness of the belt *B* which is to be joined. The wire, made up into the form represented in Fig. 1, but of considerable length, is then cut into short lengths, suitable for the width 45 of belt to be joined.

The ends of the belt material *B* to be joined are provided with holes, as at *d e*. The hooked ends *b*, in the condition shown in Fig. 1, are inserted from the outer face of one end 50 of a belt, *B*, through the holes *d*, and then through the holes *e* of the opposed end of the belt material, from its inner side, as in Fig. 3, and thereafter the hooked ends of the fingers are drawn up through the holes *e* and 55 bent over snugly, as represented by three of the fingers in Fig. 3.

As represented by dotted lines, Fig. 3, a second hook may be added, if desired.

I claim—

As an improved article of manufacture, a belt-hook composed of wire bent to form laterally-projecting fingers provided with hooks, the fingers extending from the holding-bars being bent down to form parts *c*, substantially 65 as shown and described, to extend from one to the opposite side of the belt, as set forth.

In testimony whereof I have signed my name to this specification in the presence of two subscribing witnesses.

JAMES THOMPSON.
